United States Patent Office

Des. 211,390
Patented June 11, 1968

211,390

LIGHTING FIXTURE STAND

Leroy R. Woods, 16220 Armstead St.,
Granada Hills, Calif. 91344

Filed June 5, 1967, Ser. No. 7,351

Term of patent 14 years

(Cl. D48—20)

FIG. 1 is a perspective view of my new design;
FIG. 2 is a front view thereof; and
FIG. 3 is a right side view thereof.

The broken line showing of a lamp unit is for illustrative purposes only.

I claim:

The ornamental design for a lighting fixture stand, substantially as shown and described.
